HEATING SYSTEM

George D. Bower, Columbia Heights, Minn., assignor to Minneapolis - Honeywell Regulator Company, Minneapolis, Minn., a corporation of Delaware

Application December 11, 1937, Serial No. 179,318

5 Claims. (Cl. 236—16)

This invention relates to a heating system and more particularly to one embodying a coal fired warm air furnace having automatically controlled draft and check dampers for controlling the rate 5 of combustion in the furnace, and a fan for circulating air through the heating chamber of the furnace and a space to be heated.

During times when the space temperature is at a high enough value, and the dampers are 10 in their draft retarding positions, it may be necessary to add fuel to the furnace. If this is done while the dampers are in their draft retarding positions, there is a danger of smoke and gases issuing from the firing door of the furnace. In 15 order to eliminate this danger, the check damper should be closed so that the draft through the stack will be increased, and to get the best results, the draft damper should remain closed in order that all the air entering the furnace will 20 enter through the firing door, thus reducing to a minimum the possibility of any smoke or gases issuing from the firing door.

I achieve these results in my invention by 25 providing means whereby the dampers may be manually moved from a draft retarding position to an intermediate firing position wherein both dampers are closed, and means for causing the dampers to return to their draft retarding positions should they be manually moved beyond 30 their firing positions to a position wherein the draft damper starts to open. Means are also provided for insuring that the dampers will automatically be returned to their draft retarding positions, should the attendant neglect to do 35 this manually with the result that the furnace temperature attains an excessive value.

It is often desirable to utilize the system for 40 circulating unheated air during hot weather when there is no fire in the furnace, in which case means are provided for causing the fan to operate when the temperature of the space is above a predetermined value. Provision is made for normally maintaining the dampers in their draft retarding positions during this time, from which 45 positions they may be manually moved to draft producing positions should it be desirable to burn trash in the furnace to supply heat to the space during an unseasonable cold spell for example. Means are provided for causing the dampers to 50 return to their normal draft retarding positions upon the attainment of a predetermined high temperature in the heating chamber, in which position they will remain until manually moved again.

55 It is an object of my invention to provide an

improved control means for a furnace provided with draft and check dampers for controlling the rate of combustion in the furnace.

It is a further object of my invention to provide a novel damper control system for a warm air furnace combined with a circulating fan that may be automatically operated in winter or summer to circulate heated or unheated air through a space to be controlled.

More specifically, it is an object of my invention to provide a system for causing the draft dampers of a furnace to move to draft retarding or draft producing positions according to the temperature of a space being heated, in combination with means whereby the dampers may 10 be manually moved to an intermediate position for firing purposes, and means whereby they will be automatically returned to draft retarding positions should they be moved manually beyond the intermediate position, in which position the 15 check and draft dampers are both closed.

Other objects will become apparent upon a study of the specification, claims and drawings, in which like parts are represented by like reference characters, and in which:

Figure 1 is a schematic view of my improved heating system;

Figure 2 is a perspective view of the damper operating arm assembly; and

Figure 3 is a view in cross section of the damper 30 operating arm assembly and associated parts.

Referring to Figure 1 a warm air furnace is represented by the reference character 10. This furnace includes a firing door 11, a stack 12, warm air ducts 13 and 14, a draft damper 15 and 35 a check damper 16. A draft operating arm 17 is provided for operating the draft and check dampers and is connected to said dampers by means of cables or the like 18 and 19, respectively, cable 18 passing over pulleys 20 and 21 and 40 cable 19 passing over a pulley 22. Rotation of arm 17 in a clockwise direction will cause damper 16 to close and damper 15 to open. It will be noted that cable 18 is provided with a certain amount of slack so that damper 16 will be closed 45 before damper 15 will start to open, thus permitting both dampers to be closed at the same time.

For circulating air through the heating chamber of the furnace 10 and the space or spaces to be heated, a blower 25 is provided, this blower 50 having a return duct 26 connected to the blower inlet, the outlet of said blower being in communication with the heating chamber of the furnace. A motor 27 is provided for operating the blower 25 and is connected to said blower by 55

means of a belt 28 passing over pulleys 29 and 30 of the motor and blower, respectively. Motor 27 is provided with terminals 31 and 32 which are connected to a source of power in a manner 5 to be later explained.

Mounted in the heating chamber of the furnace is a bimetallic element 23 connected at one end to a rod 24 which is in turn connected to switches 33, 34, and 35, respectively, to cause 10 the same to be tilted in response to temperature changes in the heating chamber in a well known manner. Switch 33 includes a mercury element 36 and contacts 37 and 38, these contacts being normally open as shown. Switch 34 includes a 15 mercury element 40 and contacts 41 and 42, this switch being normally in a closed position, and switch 35 includes the mercury element 43 and contacts 44 and 45, said contacts being normally open. Upon the attainment of a predetermined 20 temperature in the heating chamber bimetallic element 23 will cause switch 33 to be tilted to closed position, upon the attainment of a higher temperature in the heating chamber the switch 34 is tilted to open position and upon the attainment 25 of a still higher temperature in the heating chamber switch 35 will be tilted to closed position.

Mounted in the space to be heated is a thermostat generally indicated by the reference character 50, this thermostat including a bimetallic 30 element 51 and arms 52 and 53 carried thereby. Fixed contacts 54 and 55 cooperate with the arms 52 and 53, respectively. Arm 52 is made flexible and is arranged to engage contact 54 before arm 53 engages contact 55. When the temperature 35 in the space drops to a low enough value after engagement of arm 52 with contact 54, the arm 52 will be caused to bend and permit arm 53 to engage contact 55.

Controlled by the thermostat 50 is a relay generally indicated by the reference character 60, 40 this relay including a coil 61, an armature 62, and switch blades 63, 64, and 65. A fixed contact 66 cooperates with the switch blade 63, contacts 67 and 68 cooperate with the switch blade 64, and contact 69 cooperates with the switch blade 65. When the relay is deenergized, blade 64 is in engagement with the contact 68 and the blades 63 and 65 are out of engagement with their respective contacts. Upon energization of 50 the relay 60, blades 63, 64, and 65 move into engagement with contacts 66, 67, and 69, respectively.

For causing the operation of the arm 17, a motor 70 is provided, this motor including an armature 72 and field windings 73 and 74. Winding 73 is termed a lifting winding, energization of which in conjunction with winding 74 causes the damper arm 17 to move the dampers to a draft producing position and winding 74 is a holding winding and functions to hold the damper arm in its draft producing position as long as this winding remains energized. The arm 17 is mounted on a shaft 75 which is connected to the armature 72 through suitable reduction gearing 76.

Referring more particularly to Figures 2 and 3 it will be noted that shaft 75 is mounted through bearings 71 and 77 which are in turn mounted in stationary walls 78 and 79. Fixedly mounted on 70 the shaft 75 is a driven gear 80 from which projects a pin 81. Mounted in the wall 78 are pins 82 and 83 which are arranged in the path of movement of the pin 81 and serve to limit the amount of rotation of the gear 80 and accordingly of the shaft 75. To one end of the shaft 75

is rigidly connected an arm 85 which is normally biased in one direction by a spring 86, this spring causing the shaft 75 to rotate in a direction to cause arm 17 to move in a counter-clockwise direction as viewed in Figure 1.

To the opposite end of shaft 75 is connected the arm 17. Fixedly mounted on this end of the shaft is a clutch member 90, said clutch member including a disc portion 91 and a cylindrical portion 92 having a flange 93 at the inner end. Pins 10 94 are provided in the disc portion 91 and these cooperate with apertures 95 in the arm 17. Arm 17 is arranged for slidable movement on the cylindrical portion 92 of the clutch member 90 and is biased towards clutching position by a 15 spring 96 which is positioned about the cylindrical portion 92 and between the arm 17 and the flange 93 as clearly illustrated in Figure 3. Concentrically mounted with respect to the cylindrical portion 92 is a cylindrical portion 97 rigid 20 with the arm 17 extending inwardly from the arm 17, this cylindrical portion being provided with a cam surface 98.

When the arm 17 is in the clutched position as illustrated in Figure 3 it is clutched to the 25 shaft 75 for rotation therewith. As the arm is now moved to the left, as viewed in Figure 3, against the force of spring 96 to a position in which the apertures 95 are out of engagement with the pins 94, the arm 17 may be rotated with 30 respect to the shaft 75 and the clutch 90. A switch 100 is mounted in the path of movement of the cam 98, this switch including a movable arm 101 and a fixed contact 102 is connected to the fixed wall 79 by means of a bracket 103 and the insulating material 104. The cam 98 and the switch arm 101 are so related with respect to one another that if the arm 17 is declutched and rotated in a clockwise direction to a position in which both dampers 15 and 16 are closed, the 40 arm 101 will not be engaged by the cam 98. Should the arm 17 be rotated past this position to a position in which the draft damper 15 starts to open, cam 98 engages the arm 101 and forces it against the fixed contact 102 for a purpose to 45 be later described.

Also mounted on the walls 78 and 79 is the insulating member 105 on which is mounted the switch arm 106 which normally engages a fixed contact 107 as illustrated in Figure 1. Mounted 50 on the shaft 75 is a cam 109 which engages a cam surface 108 of the arm 106 causing it to move out of engagement with the contact 107 upon rotation of the shaft to a position in which the arm 17 is in the draft producing position, 55 that is, the check damper 16 is closed and the draft damper 15 is open.

For supplying power to the blower motor 27 and the damper motor 70, lines 110 and 111 are provided, these lines being connected to a suitable 60 source of power (not shown). A step-down transformer 112 is provided for supplying low voltage power to the relay 60, this transformer including a high tension primary 113 connected by means of conductors 114 and 115 to the lines 65 110 and 111 and a low tension secondary 116.

A switch 126 is provided for changing the system from a warm air circulating system in the winter time to an unheated air circulating system in the summer time as will be later explained. 70 This switch includes a switch blade 127 and fixed contacts 128 and 129 for cooperation therewith. This blade, as illustrated, is in the winter position and when moved into engagement with contact 128 it is in the summer position.

lished through the winding 73 as follows: from the line 110 through conductor 130, switch arm 127, contact 129, conductors 131, 160, contact 102, switch arm 101, conductors 161, 136, 137, switch arm 106, contact 107, conductor 138, winding 73 and conductors 139 and 140 to the line 111. Current also flows through winding 74 by the following circuit: from line 110, conductor 130, switch arm 127, contact 129, conductors 131, 160, 10 contact 102, switch arm 101, conductors 161, 136, and 141, winding 74, and conductor 140 to the line 111. Armature 72 of motor 70 is now caused to rotate and continues to rotate as long as this circuit is maintained. When the shaft 75 has rotated through a distance which is equivalent to the amount of manual rotation of arm 17 or until pins 94 and apertures 95 are in registry, the spring 96 will cause reclutching of arm 17 and the shaft 75 which in turn causes the cam 98 to move 20 out of engagement with the switch arm 101, which breaks the above described circuits through the windings 73 and 74. If the room thermostat is still satisfied at this time, that is, it is not calling for heat, there will be no circuit through the 25 windings 74 and 73 and the spring 86 will cause arm 17 to move back to its draft retarding position. It will thus be seen that the operator may not manually move arm 17 beyond the firing position toward the draft producing position while 30 the room thermostat is satisfied and have it remain in this position since the damper motor 70 will immediately take control of the arm 17 and cause it to move back to its original draft retarding position.

35 While it is intended that the operator move the arm 17 back to its draft retarding position after he has finished firing the furnace, should he fail to do this the motor 72 will resume control over the arm 17 when the thermostat 50 again calls for heat since the circuit originally described through the windings 73 and 74 will become reestablished and cause shaft 75 to rotate until the arm 17 is clutched with the shaft 75 and the arm will be moved to its draft producing position as originally described.

It will be apparent that if the dampers are in their draft producing positions caused by a lowered temperature in the space being heated and the attendant desires to fire the furnace, the 50 arm 17 may be manually moved back to its intermediate position in the same way as from the draft retarding to the firing position. Should the attendant leave the dampers in this position there is no possibility of any danger to the furnace since if the temperature of the heating chamber rises to a high enough value the current through the holding coil 74 will be interrupted either by reason of the opening of switch 34 or the satisfaction of the thermostat 50 whereupon 55 spring 86 will cause shaft 75 to move toward the draft retarding position and after it has moved back to the firing position it will be again clutched with the arm 17 whereupon the arm will also be moved to its draft retarding position.

60 Should it be desired to use the system for circulating unheated air during the summer time when the temperature of the space rises above a certain high predetermined value, switch blade 127 is moved into its summer position in engagement with the contact 128. When the thermostat 50 is in the position illustrated indicating that the temperature of the space is above a predetermined value a circuit will be established through the motor 27 as follows: from the line 75 110 through conductor 130, switch blade 127, con-

tact 128, conductors 165, 157, contact 68, switch blade 64, conductor 152, terminals 31, 32 of the motor 27, and conductor 153 to the line 111. Motor 27 will continue to operate as long as switch blade 64 is in engagement with contact 68 or in other words, as long as relay 60 is deenergized. Should the temperature of the space drop below the predetermined value, the relay 60 will be energized as formerly described and switch blade 64 will move out of engagement with contact 68 thus interrupting the circuit through the motor 27. With the switch blade 127 in engagement with contact 128 there will be no circuit through the damper motor 70 and the dampers will be held in their draft retarding positions as illustrated.

Should there be an unseasonable cold spell during the summer time it may be desirable to burn some trash in the furnace in order to raise the temperature up enough to supply the necessary heat to the space to bring the temperature up to a comfortable point. In order to facilitate the combustion of the trash the dampers should be moved to draft producing position. This may be done by declutching the arm 17 from the shaft 75 and manually moving the same to a position in which the check damper is closed and the draft damper is open. In this position of the arm 17 it will be understood that switch arm 101 is in engagement with contact 102. The temperature of the heating chamber will rapidly rise to a point wherein the switch 35 will move to closed position. A circuit including this switch is now established through the lifting winding 73 of the motor 70, this circuit being as follows: from line 110 through conductor 130, switch blade 127, contact 128, conductors 165, 156, contacts 44 and 45 of switch 35, conductors 155, 132, 160, contact 102, switch blade 101, conductors 161, 136, 137, switch arm 106, contact 107, conductor 138, 40 winding 73, conductors 139 and 140 to the line 111. The holding winding 74 is also energized through the following circuit: from line 110 through conductor 130, switch blade 127, contact 128, conductors 165, 156, contacts 44 and 45 of switch 35, conductors 155, 132, 160, contact 102, switch blade 101, conductors 161, 136, 141, winding 74 and conductor 140 to line 111. The motor will not rotate until the arm 17 becomes clutched with the shaft 75 which takes place when the shaft 75 has rotated to a position in which the pins 94 and apertures 95 are in registry with one another, whereupon spring 96 moves arm 17 into clutching relationship with shaft 75, whereupon the switch arm 101 moves away from contact 102. 55 No current now flows through either the winding 73 or 74 of the motor 70 and the spring 86 causes the shaft 75 and the arm 17 to rotate back to the draft retarding position.

When the switch 35 tilts to its closed position, 60 the motor 27 is energized, regardless of the position of the thermostat, the circuit through the motor 27 with the thermostat calling for heat being as follows: from the line 110 through conductor 130, switch arm 127, contact 128, conductors 165, 156, contacts 44 and 45 of switch 35, conductors 155 and 150, contacts 38 and 37 of switch 33, it being understood that this switch is closed when the switch 35 is closed, conductor 151, contact 67, switch blade 64, conductor 152, 70 terminals 31 and 32 of motor 27 and conductor 153 to the line 111. If the thermostat is not calling for heat, the motor will be energized through the previously described circuit, which circuit is independent of switch 35. It should be noted at 75

Operation

With the parts as illustrated the room thermostat 50 is satisfied, that is, it is not calling for heat. The draft damper 15 and the check damper 16 are in the draft retarding positions, motors 21 and 70 are both deenergized and no air is being circulated by blower 25 through the furnace and the space being heated. Let it be assumed now that the temperature in the space being heated falls to a predetermined value whereupon the arm 52 engages the contact 54. This does not in itself cause relay 60 to become energized but when the temperature of the space drops still further and arm 53 engages the contact 55 a circuit is established through the relay coil 61 as follows: from one side of the secondary 116 of transformer 112 through conductor 120, contact 54, arms 52 and 53 of thermostat 50, contact 55, conductors 121, 122, coil 61, and conductor 123 to the other side of secondary 116. Energization of relay 60 causes blades 63, 64, and 65 to move into engagement with contacts 66, 67, and 69, respectively. Engagement of blade 63 with contact 66 closes a holding circuit for the coil 61 which is independent of the arm 53, this circuit being as follows: from the secondary 116 through conductor 120, contact 54, arm 52 through the bimetallic element 51, conductor 124, contact 66, blade 63, conductors 125, 122, coil 61 and conductor 123 to the other side of the secondary 116. Since the relay coil 61 remains energized until the arm 52 moves away from contact 54 it will be understood that the coil 61 is deenergized at a higher temperature than that at which it became energized.

Movement of blade 65 into engagement with contact 69 causes the operation of the damper motor 70. The lifting coil 73 of said motor is energized through the following circuit: from the line 110 through conductor 130, switch arm 127, contact 129, conductors 131, 132, 133, contact 42 through the mercury element 40 to the contact 41, conductor 134, switch blade 65, contact 69, conductors 135, 136, 137 through the switch arm 106, contact 107, conductor 138 through the winding 73 and conductors 139 and 140 to the line 111. Current also flows through the holding coil 74 as follows: from the line 110, conductor 130, switch blade 127, contact 129, conductors 131, 132, 133, switch 34, conductor 134, switch blade 65, contact 69, conductors 135, 136, 141 through the winding 74 and conductor 140 to the line 111. The armature 72 now starts to rotate causing rotation of shaft 75 in such a direction that arm 17, as illustrated in Figure 1, is moved in a clockwise direction. This rotation continues until the check damper 16 is closed and the draft damper 15 is opened at which time the pin 81 engages the stop 82 and the cam 109 causes switch arm 106 to move out of engagement with the contact 107. Since this switch blade 106 is in the circuit through the lifting winding 73 it is obvious the current will no longer flow through this winding. The current through the winding 74 is just sufficient to counteract the effect of spring 86 on arm 85 so that said spring will not cause rotation of arm 17 in a counter-clockwise direction as long as winding 74 remains energized.

Since the dampers have now been moved to their draft producing positions, the rate of combustion in the furnace increases with an attendant increase in temperature in the heating chamber. When the temperature reaches a certain high value, bimetallic element 23 causes switch

33 to be tilted to a position in which contacts 37 and 38 are bridged by the mercury element 36. A circuit is now established through the blower motor 27 which circuit is as follows: from the line 110 through conductor 130, switch blade 127, contact 129, conductors 131, 132, 150, contacts 38 and 37, conductor 151, contact 67, blade 64, which it will be remembered is in engagement with the contact 67 since the relay 60 has been energized, conductor 152, terminal 31 of the blower motor 27 through the motor to terminal 32 and conductor 153 to the line 111. Operation of the motor 27 causes the blower 25 to circulate the air in the heating chamber through the space to be heated. Motor 27 will continue to operate until the room thermostat 50 has become satisfied, thus deenergizing the relay 60 and breaking the circuit through the blower motor, or should the temperature of the heating chamber fall below the value required to tilt the switch 33 to closed position, the switch will be opened and cause the circuit through the motor 27 to be interrupted.

Should the temperature in the heating chamber rise to an excessive value or to a value sufficient to cause switch 34 to tilt to open position, the aforedescribed circuit through the holding winding 74 of the damper motor 70 will be interrupted since this circuit includes the switch 34 and the spring 86 will cause the damper operating arm 17 to move back to the original position as illustrated and cause the dampers 15 and 16 to move in their draft retarding positions.

Should it so happen that the temperature of the heating chamber continues to rise for any reason after the room thermostat is satisfied and the dampers are in their draft retarding positions, to a point sufficient to cause switch 35 to be tilted to closed position, a circuit will be established through the motor 27 which is independent of the room thermostat 50 so that this excessive heat in the heating chamber may be dissipated. This circuit through the motor 27 is now as follows: from the line 110 through conductor 130, switch blade 127, contact 129, conductors 131, 132, 155, contacts 45 and 44, conductors 156, 157, contact 68, switch blade 64, conductor 152, terminals 31 and 32 of the motor 27 and conductor 153 to the line 111. Motor 27 will thus continue to operate until the temperature of the heating chamber drops to a point wherein switch 35 is tilted to open position.

Assume now that the room thermostat is satisfied and that the parts are all in the positions illustrated in Figure 1. If now it is desired to throw some fuel in the furnace, the check damper 16 should be closed and the draft damper 15 should remain closed so that when the door 11 is open there will be a strong circulation of air over the top of the fire and through the stack 12 to prevent smoke, etc. from issuing out of the door 11. In order to move the damper 16 to its closed position the arm 17 may be moved inwardly or to the left as viewed in Figure 3 until apertures 95 and pins 94 are out of engagement with one another, whereupon the arm 17 may be rotated with respect to the shaft 75. When so rotated the spring 86 exercises no effect whatever over the damper arm 17 so that the arm will remain in the position in which it is placed as long as it is declutched from the shaft 75. Should the attendant through mistake rotate arm 17 too far or to a position in which the draft damper 15 begins to open, the cam 98 carried by the arm 17 will engage the switch arm 101 causing it to engage the contact 102. A circuit will now be estab-

this point that motor 27 is energized whenever switch 35 is tilted to closed position regardless of the position of the summer-winter switch 126. The heat in the heating chamber of the furnace 10 is now circulated through the space being heated thus causing a rise in the temperature of said space and the motor 27 will continue to operate until the temperature in the heating chamber falls below the value required to cause the closing of switch 35. If the thermostat becomes "satisfied," or moves to a position calling for cooling, the motor will continue to operate until the thermostat is again calling for heat and switch 35 is open, whereupon the motor will stop. 15 The dampers 15 and 16 will remain permanently in their draft retarding position when the switch 126 is in its summer position until such time as the attendant manually moves them to their draft producing positions.

20 It will thus be seen that I have devised a damper control system for a warm air furnace wherein the dampers are under the control of the room thermostat and a switch responsive to temperatures of the heating chamber of the furnace and in which, should it be desired to fire the furnace the dampers may be manually moved to an intermediate firing position wherein both dampers are closed, but should the dampers be manually moved beyond this intermediate position they will again be moved back to draft retarding position, assuming this was the position of the dampers before they were manually moved to the firing position. It will also be seen that with my system the fan may be operated in the 25 summer time to circulate unheated air through the space which is normally being heated in the winter time when the temperature in said space rises above a desired value, at which time the dampers are normally in their draft retarding positions and remain in these positions unless they are manually moved to the draft producing positions when it is desired to start a fire in the furnace and that they will be moved to their normal draft retarding positions as soon as the temperature of the furnace rises above a certain predetermined value. It will also be seen that regardless of the temperature of the space being supplied with heated or unheated air and regardless of the position of the summer-winter 30 switch the blower 25 will always be operated whenever the temperature of the furnace reaches an excessive high temperature thus preventing any possible danger by reason of the overheating of said furnace by distributing the heat throughout the building being heated.

While I have illustrated and described a preferred form of my invention, it will be apparent that it is capable of many modifications by those skilled in the art and I wish it to be understood that the invention is limited only by the scope of the appended claims.

I claim as my invention:

1. In a heating system, a furnace, damper means for controlling the rate of combustion in said furnace, actuating means responsive to the attainment of predetermined conditions for causing movement of said damper means to draft producing and draft retarding positions, means whereby control of said actuating means over the 55 damper means may be temporarily withdrawn and the damper means manually moved to an intermediate firing position regardless of the existing condition and without causing the operation of the actuating means so that said damper means may normally be maintained in said firing

position for any desired period of time, and means responsive to manual movement of said damper means from draft retarding position, past firing position towards draft producing position for restoring control of said actuating means over 5 said damper means.

2. In a furnace, damper means for controlling the rate of combustion in said furnace, said damper means having a draft producing position, a draft retarding position, and an intermediate firing position, a motor for moving said damper means from draft retarding to draft producing position and holding the damper means in draft producing position, biasing means for causing movement of said damper means from draft producing position to draft retarding position, condition responsive means for causing the energization and deenergization of said motor, means whereby control of the motor and biasing means over the damper means may be 10 temporarily removed and the damper means manually moved from draft retarding to firing position, without causing energization of said motor so that said damper means may normally be maintained in said firing position for any desired period of time and means responsive only to movement of the damper means from draft retarding past firing position towards draft producing position for restoring control of said motor and biasing means over said damper 15 means.

3. In a heating system, a furnace, damper means for controlling the rate of combustion in said furnace, said damper means being movable into draft producing, a draft retarding and a 20 firing position, actuating means for causing movement of said damper means into draft producing and draft retarding positions, condition responsive means controlling said actuating means, means whereby said damper means and 25 said actuating means may be declutched and said damper means manually moved to the firing position without causing the operation of said actuating means so that said damper means may normally be maintained in said firing position 30 for any desired period of time, means responsive to the operation of said actuating means by the condition responsive means for causing said actuating means and said damper means to be re-clutched, and means responsive only to declutching of said actuating means and damper means 35 and manual movement of said damper means from draft retarding position, past firing position towards draft producing position for causing direct reclutching of said damper means and 40 45 actuating means.

4. A damper motor comprising a driving shaft, a damper actuating member, clutch means between said shaft and damper actuating member, said clutch means including means for holding the damper actuating member in a different axial position with respect to said shaft when said shaft and member are declutched, from the position when said shaft and member are clutched, switch means, circuit means whereby said motor 50 is energized in response to actuation of said switch means, means normally holding said switch means in inoperative position, means responsive only to rotation of said damper actuating arm relative to said shaft through a distance 55 great enough to cause damper means actuated thereby to move from draft retarding position to draft producing position to cause actuation of said switch and rotation of said driving shaft, and means responsive to rotation of said driving 60 65 70 75 shaft.

shaft to cause reclutching of said shaft and damper actuating member.

5. In combination, a furnace, damper means for controlling the rate of combustion in said furnace, said damper means having a draft producing position, a draft retarding position, and an intermediate firing position, an actuator for said damper means, biasing means for said actuator tending to move said actuator to a position 10 in which said damper means is in draft retarding position, a motor for moving said actuator relatively quickly against said biasing means to a position in which said damper means is in draft producing position, condition responsive 15 means for causing the energization and deenergization of said motor, means for declutching said damper means from said actuator whereby said

damper means may be manually moved to the firing position, means responsive to movement of said actuator by reason of energization of said motor to cause said damper means and said actuator to be reclutched, a switch for causing 5 the energization of the motor independently of said condition responsive means, and means responsive to declutching of said damper means and movement of the same from draft retarding position past firing position towards draft producing position for causing closure of said switch and accordingly energization of said motor to effect reclutching of said damper means and actuator, said switch being so located as not to be closed by the manual declutched movement of 10 15 said damper means to firing position.

GEORGE D. BOWER.
